UNITED STATES PATENT OFFICE

ERNEST B. MILLER AND WALTER L. EDEL, OF BALTIMORE, MARYLAND, ASSIGNEES TO
THE SILICA GEL CORPORATION, OF BALTIMORE, MARYLAND, A CORPORATION OF
MARYLAND

OSCILLATING TYPE REFRIGERATION PLANT

Application filed October 28, 1925. Serial No. 65,465.

The present invention relates to refrigeration apparatus of the adsorption type in which a liquid is evaporated, and the vapor adsorbed in a solid porous adsorbent. It is a modification of the invention described and claimed in Patent 1,729,081 granted to E. B. Miller, September 24, 1929. According to this prior invention, the refrigeration is obtained by evaporating a liquid, such as water from brine and adsorbing the vapor in a solid porous adsorbent such as silica gel; the adsorption being carried on in substantially the total absence of permanent gases.

One of the objects of the present invention is to provide an apparatus in which pumps and other power driven devices to maintain a vacuum or produce a refrigerating effect are eliminated.

Another object is to provide an apparatus that is completely automatic in operation, and at the same time is fool-proof so that it will function indefinitely without requiring attention.

Another object is to provide an apparatus of this type with means for freeing the interior thereof of all permanent gases and accomplishing this result, without a power pump or other machinery, even more effectively than with a vacuum pump alone.

Another object is to provide an apparatus wherein the adsorbent is disposed so that the maximum surface thereof is presented to the vapor with the result that the vapor is not required to penetrate deeply into a bed or layer of adsorbent.

Another object is to provide a simplified apparatus of this character that can be manufactured to sell at a relatively low price.

Other objects and features of novelty will be apparent from the following description taken in connection with the accompanying drawings, in which

Fig. 1 is a front elevation of one form of refrigerating apparatus constructed in accordance with the present invention, certain parts being broken away;

Fig. 2 is a half side and half sectional elevation of the same, parts being broken away;

Fig. 3 is an enlarged fragmentary vertical

section taken substantially on the line 3—3 of Fig. 2;

Fig. 4 is a horizontal sectional view taken substantially on the line 4—4 of Fig. 3;

Fig. 5 is an enlarged sectional view of a portion of one of the adsorber sections;

Fig. 6 is a diagrammatic view showing the adsorber assembly in its central position;

Fig. 7 is a similar view showing the adsorber assembly at the right hand end of its swing;

Fig. 8 is an elevation partly in section of an adsorber made up of pipes; and

Fig. 9 is a plan view of the "pipe" adsorber.

Briefly stated, an apparatus according to the present invention comprises two adsorbers A and B carried by a frame C which is fulcrumed at D on a stationary frame E.

While one adsorber is adsorbing vapor from the evaporator 44, the adsorbent material in the other adsorber is being activated, communication between the adsorbers and evaporator being controlled automatically by valves. The alternate action of the adsorbers is obtained by automatically tilting the same, and this movement is utilized to control the heat for activating and the shifting of the valves. During activation, the adsorbers are automatically freed of permanent gases by exhausting the vapor therefrom and thus sweeping out any permanent gases. If desired the vapor may be condensed and returned to the evaporator.

The apparatus, according to this invention, may take many forms. The one shown in the drawings, somewhat diagrammatically, is merely by way of illustration.

The two frames E and C may be made conveniently of angle bars 10 or other suitable shapes. The stationary frame E supports two pivot blocks 11, one on each side of the framework, each block having two pivot points 12. The adsorbers are supported on these pivot points for tilting movement and for this purpose the frame C, at opposite sides thereof, is provided with blocks, each having a pair of V shaped notches 14 adapted to cooperate with the pivots 12. The frame 13 carries two adsorbers A and B inclined one to the other as shown in Fig. 1.

Each adsorber comprises a plurality of sections 16, the construction of which is shown in detail in Figs. 3 and 5. Each section consists of two cupped or flanged plates 17 which are joined together at their marginal edges (as by welding) and a pair of spaced screens 18 mounted centrally between said plates. The spaces between the screens and plates are filled with a solid porous adsorbent, such spaces being relatively thin, so that the vapor being adsorbed comes into contact with the greatest possible surface of the adsorbent material rapidly and without the resistance that would be presented by a deep or thick bed of adsorbent. Not only does this construction provide for rapid adsorption of the vapor, but it also permits a speedy activation of the adsorbent.

The interiors of the adsorbent sections 16 are in communication at their upper ends through short lengths of pipe 19, and are secured to the frame C near their upper ends in any suitable manner, as by means of the bolts 21, spacing sleeves 22, clamping bars 23, and nuts 24, the bolts and sleeves being on the outside of the sections and secured to the frame C, the bars 23 passing between the sections and bearing against one side of each, so that the sections are drawn together and towards said frame C by the bolts and nuts. At their lower ends, the sections are secured to two spaced angle bars 25 by angles 27 and said bars are supported from the frame C by means of two vertical rods 26, one at the front and the other at the back of the apparatus. Each adsorber A and B is surrounded by a heat insulating casing 28, which is open at the top and bottom, the bottom edges being curved on the arc of a circle as shown at 28^a, Fig. 1.

The frame C also carries a valve casing 30 which is disposed between the two adsorbers and at the top of the apparatus. As clearly shown in Figs. 3 and 4, this casing is divided into two chambers 31 and 31^a by a vertical and transverse partition 32. Each of these chambers is connected to one of the adsorbers by means of pipes 33 and 33^a respectively. Communication between the two chambers is obtained by a conduit 34 extending through the partition and provided with a central passageway 35. At its opposite ends this conduit is formed with the valve seats 36 and 36^a with which the valves 37 and 37^a respectively cooperate. As shown, these valves are carried by arms 38 and 38^a respectively rotatively pivoted at 39 and 39^a to the valve casing 30. To obtain the proper alternate opening and closing of the valves, they are connected by a link 40 which extends through the conduit 34, the ends of the link being pivotally attached to the respective valves at 40^a.

The conduit 35 is in communication with the evaporator 44 through pipe 41, the flexible metallic bellows 42 and the pipe 43. The

pipe 41 being carried by the tiltable frame C, and the pipe 43 being supported on the stationary part of the apparatus, it is necessary to provide a flexible connection between the two and this is obtained by the bellows 42, carried by the stationary frame E.

The evaporator 44 is designed to contain a suitable liquid such as brine solution and is entirely sealed from the atmosphere. It may be made as a welded metallic casing and provided with a plurality of chambers 45 into which suitable ice trays (not shown) may be slid in the usual manner. A drain 47 is provided at the bottom of the evaporator and may be closed by any suitable means such as valve 47^a. From time to time, the evaporator must be supplied with make-up water and for this purpose a valve controlled inlet 44^a may be provided which can be connected with a water main if desired, or the vapor driven off from the adsorbers during activation may be condensed and returned to the evaporator.

Any suitable means may be provided for furnishing heat to activate the adsorbers. As shown, a plurality of gas burners 50 are mounted in a casing 51 below the adsorbers and carried by the stationary frame E. The top of the casing is open and its upper edges are curved to correspond with the curved edges 28^a of the adsorber casings so that these casings substantially join each other. The burners 50 may be of the usual Bunsen type and supplied from a gas main 53. Pilot lights 54, mounted adjacent burners 50 are also connected to the gas main 53.

The supply of gas to the burners 50 is controlled automatically. This may be accomplished by employing the tilting movement of the adsorbers to activate the gas valve. When the apparatus is in position shown in Fig. 1, the adsorber B is being activated, while adsorber A is adsorbing water vapor. At this time, the gas burners 50 are burning and furnishing heat to activate the adsorber B. After a time the adsorbers will tilt so that frame C will be supported on all the pivot points 12. In other words, the adsorbers will occupy a position midway of the total swinging movement. For this purpose, the gas to the burners should be cut off so that there will be no further activation of adsorber B. Then after a time, the adsorbers will swing further in a clockwise direction as viewed in Fig. 1 so that adsorber A will be brought to have its casing register with the burner casing 51. At this time, the gas should be turned on so as to activate adsorber A. These results are obtained by providing a special two-way cock 55 in the gas main 53. This cock 55 is provided with an operating handle or lever 56, the further end of which is formed with a slot 57. A pin 58, carried by the adsorber A, operates in the slot 57 so that tilting of the adsorber swings the lever 56.

The evaporator 44 is designed to contain a suitable liquid such as brine solution and is entirely sealed from the atmosphere. It may be made as a welded metallic casing and provided with a plurality of chambers 45 into which suitable ice trays (not shown) may be slid in the usual manner. A drain 47 is provided at the bottom of the evaporator and may be closed by any suitable means such as valve 47^a. From time to time, the evaporator must be supplied with make-up water and for this purpose a valve controlled inlet 44^a may be provided which can be connected with a water main if desired, or the vapor driven off from the adsorbers during activation may be condensed and returned to the evaporator.

In order to adjust the period of the tilting action, counterweights 60 may be provided which are adjustably mounted on the rods 26. By sliding these up or down, the center 5 of gravity of the adsorbers as a whole may be adjusted. These weights may be secured in adjusted positions by means of set screws 61.

When activating, it is desired that the 10 vapor evaporated from the adsorbent may be exhausted in order to sweep out all permanent gases that may have accumulated. For this purpose, the valve chambers 31 and 31^a are provided with relief valves 62 and 62^a 15 respectively, which are set so as to open when the pressure in the valve chamber exceeds the pressure of the atmosphere. These valves may open directly to the atmosphere in which case the vapor is lost and from time to time 20 must be made up by addition of water to the evaporator through valve 44^a. If desired, however, the vapor from valves 62 and 62^a 25 may be condensed and returned to the evaporator as described and claimed in said patent.

The operation of the apparatus is as follows: With the apparatus in the position shown in the drawings, vapor from the refrigerating liquid in the evaporator 44 passes through pipe 43, bellows 42 and pipe 41 into 30 the conduit 35. The valve 37^a being open, this vapor will then flow into chamber 31^a and be conducted by pipe 33^a to the adsorber A where it is adsorbed by the adsorbent material contained therein. Preferably, this material is granular silica gel such as manufactured by The Silica Gel Corporation, of Baltimore, Maryland. Other gels might be used or other solid porous adsorbents if suitable to take up the vapor of the 40 liquid refrigerant being used.

While the adsorber A is adsorbing the water vapor as stated, adsorber B will be activated, the hot gases from the burners 50 rising through the casing 28 surrounding the 45 adsorber and thereby heating the adsorbent and liberating the adsorbed vapor. The liberated vapor will pass through pipe 33 into chamber 31 and when the pressure slightly exceeds atmospheric will open relief valve 62 thereby exhausting the vapor and sweeping 50 out any permanent gases that may have accumulated in the adsorber or connected parts.

As activation continues, adsorber B will 55 gradually decrease in weight because of the vapor liberated therefrom, while adsorber A will gradually increase in weight because of water vapor being adsorbed thereby. The heat of adsorption is carried away by air passing upwardly through the adsorber A. After a time, the change in weights will be 60 sufficient to cause the combined adsorbing portion of the apparatus to tilt on the pivot block D to a position where all of the pivot points 12 are supporting the adsorbing apparatus. In this position, the valve casing 65

will be substantially horizontal and adsorber B will have swung clockwise, as viewed in Fig. 1, to a position where the open bottom of casing 28 is out of register with the burner casing 51 so that air may pass up through 70 the casing 28 and cool the adsorber. This tilting action turns lever 56 to the position illustrated by the dotted line 65 and thereby cuts off the supply of gas to the burners 50. Of course, gas is continually supplied to the 75 pilots 54 through the pipe 54^a which is connected to the gas main on the pressure side of valve 55. The adsorber assembly halts at the central position described above until the difference in weights between the two adsorber units increases enough to further tilt the same about the right hand pivot points 12. This pausing or halting in the tilting movement is an important feature of the present invention. Activation usually is effected more rapidly than the adsorption and the halting movement mentioned permits the activation of one unit to be cut off long before the other unit has ceased its adsorbing 80 action. This action also provides for the most economical use of the gas or other heating medium inasmuch as heating is not continued after the adsorbent has been substantially activated.

When the adsorber assembly tilts from the 90 central position mentioned above (shown in Fig. 6) to its right hand position, (shown in Fig. 7) the casing 28 of adsorber A is brought into register quickly with the burner casing 51, and simultaneously the gas lever 56 is 95 turned to the position indicated by dotted line 66, Fig. 1.

The adsorber assembly is designed so that its center of gravity is above or higher than the pivots 12. When the parts are in the positions shown in Fig. 1, the center of gravity of the adsorber assembly is above and slightly to the left of the left hand pivot 12. As the weights of the adsorbers change, the center of gravity moves to the right, there being no 100 movement of the assembly until after the center of gravity has crossed the vertical line through the left pivot 12. Then the assembly quickly tilts to the position shown in Fig. 6. This movement is rapid and unhesitating 110 because the center of gravity moves further to the right as the tilting continues, thereby furnishing a gradually increasing turning movement. The assembly pauses or halts in this central position until the weight of adsorber A increases sufficiently to move the center of gravity across the vertical line through the right hand pivot 12. Then the assembly tilts rapidly and without interruption 120 to the position shown in Fig. 7. This last step in the tilting movement quickly brings adsorber A to activating position, turns on the gas, and at same time places adsorber B in communication with the evaporator 44.

125 130

In swinging from the position shown in Fig. 1 to the said central position, shown in Fig. 6, the valves 37 and 37^a remain unchanged because of the arrangement of the centers of gravity thereof, and because chamber 31^a is under a pressure less than atmospheric, while chamber 31 has a pressure slightly greater than atmospheric. Thus, the high pressure being on the right hand side of valve 37 (as viewed in Fig. 3) said valve is held against its seat until after the adsorbers have swung to their extreme right hand positions. Then the pressure in chamber 31^a increases, and that in chamber 31 decreases, which changes in pressure coupled with gravity acting on the valves, cause valve 37^a to close and valve 37 to open.

After the weight of adsorber A has been decreased by activation and that of adsorber B increased by adsorption, the adsorber unit will tilt counterclockwise, to the said central position, and the sequence of operations will continue in a perfectly obvious manner.

It is evident that the apparatus will operate indefinitely without any attention except to supply make up water at intervals, which may be of several days duration.

When it is desired to change the length of the periods of activation and adsorption to accord with the amount of refrigeration desired, the counterweight 60 may be adjusted to change the center of gravity of the adsorber assembly.

Another form of adsorber section is shown in Figs. 8 and 9. Here each section comprises a header 80 having a plurality of pipes 81 welded thereto, the lower ends of the pipes being closed. A tubular screen 82 is fastened in each pipe, extending throughout the length thereof, and projecting into the header. The annular spaces between the screens and inner surfaces of the pipes are filled with silica gel or other suitable adsorbent. The headers 80 are in communication through the connectors 83 welded thereto, and the inside header is connected to the valve casing 30 by pipe 33 the same as in the adsorber previously described.

The above adsorber construction, may be employed in connection with other forms of refrigerating apparatus and are not limited to the oscillating type described herein. In both forms of adsorbers it will be noted that the path of the vapor from the central perforated screen to the outer wall of the container is extremely short and that the superficial area of the exposed surface of the adsorbent is quite large in relation to the total volume of the adsorbent in each container.

60 The feature of sweeping out permanent gases by exhausting vapor from the adsorbers during activation, is claimed in Patent No. 1,729,083, granted to E. B. Miller, et al., September 24, 1929.

65 Having thus described the invention what

is claimed as new and desired to be secured by Letters Patent is:

1. Refrigerating apparatus of the character described, including in combination, a support, a unit comprising a pair of adsorbers charged with vapor adsorbing material balanced on said support so that alternate adsorptions and activations causes said unit periodically to tilt, first one way and then the other, an evaporator containing an evaporable liquid, means to place said evaporator alternately in communication with said adsorbers, and means controlled by said tilting movement to activate each adsorber when it is disconnected from said evaporator. 70 75 80

2. Refrigerating apparatus of the character described, including in combination, a support, a unit comprising a pair of adsorbers charged with vapor adsorbing material balanced on said support so that alternate adsorptions and activations cause said unit periodically to tilt, first one way and then the other, an evaporator containing an evaporable liquid, means controlled by said tilting movement to place said evaporator alternately in communication with said adsorbers, and means to activate each adsorber when it is disconnected from said evaporator. 85 90 95

3. Refrigerating apparatus of the character described, including in combination, a support, a unit comprising a pair of adsorbers charged with vapor adsorbing material balanced on said support so that alternate adsorptions and activations cause said unit periodically to tilt, first one way and then the other, an evaporator containing an evaporable liquid, means to place said evaporator alternately in communication with said adsorbers, and means to activate each adsorber when it is disconnected from said evaporator. 100 105 110

4. Refrigerating apparatus of the character described including in combination, a support, an adsorber charged with a vapor adsorbing material balanced on said support with its center of gravity higher than said support, so that alternate adsorptions and activations cause said adsorber to rock periodically, a stationary evaporator containing an evaporable liquid, and means controlled by said rocking movements to alternately place the evaporator in, and out of, communication with said adsorber and to activate the adsorber when out of communication with said evaporator. 115 120 125

5. Refrigerating apparatus of the character described, including in combination, a stationary evaporator containing an evaporable liquid, a pair of adsorbers charged with a vapor adsorbing material, a valve device controlling communication between said evaporator and adsorbers, and means controlled by changes in the weights of said adsorbers to alternately activate said adsorbers, 130

and shift said valve device to place the evaporator alternately in communication with said adsorbers.

6. Apparatus of the character described including in combination, an evaporator, a pair of adsorbers adapted to be placed in communication with said evaporator, means supporting said adsorbers for rocking movement constructed and arranged so that the adsorbers swing from one end of their movement to a central position, pause, and then swing to the other end of their movement, means to activate each adsorber when at one end of its movement, and means to cut off communication with said evaporator when being activated.

7. Apparatus of the character described including in combination an evaporator containing evaporable liquid, a pair of rigidly connected adsorbers adapted to be placed in communication with said evaporator, a pair of parallel pivots supporting said adsorbers for rocking movement, the parts being constructed and arranged so that the adsorbers swing on one pivot from one end of their movement to a central position supported on both pivots where there is a pause in the swinging movement, and then swing on the other pivot to the other end of their movement, means to activate each adsorber when at one end of its movement, and means to cut off communication with said evaporator when being activated.

8. Refrigerating apparatus of the character described including in combination, a stationary evaporator containing an evaporable fluid, an adsorber charged with a vapor adsorbing material in communication with said evaporator, means supporting said adsorber for tilting movement effected by the changes in weight thereof, means to alternately place said evaporator in, and out of, communication with said adsorber, and means to activate said material, controlled by the tilting movement of said adsorber.

9. Refrigerating apparatus of the character described, including in combination, an evaporator containing an evaporable liquid, an adsorber charged with a vapor adsorbing material in communication with said evaporator, one of said parts being stationary, means to support the other for swinging movement in steps effected by changes in the weight thereof, such means being constructed to provide a dwell at each end and the middle of the swinging movement, means to cut off communication between said evaporator and adsorber at one end of said movement and activate said adsorber, controlled by said swinging movement.

10. Refrigerating apparatus of the character described, including in combination, an evaporator containing an evaporable liquid, an adsorber charged with a vapor adsorbing material in communication with said evapo-

rator, one of said parts being stationary, means to support the other for swinging movement in steps effected by changes in the weight thereof, such means being constructed to provide a dwell at each end and the middle of the swinging movement, means to cut off communication between said evaporator and adsorber at one end of said movement and means controlled by said swinging movement to activate said adsorber when said communication is cut off.

11. Refrigerating apparatus of the character described including in combination, an evaporator containing an evaporable liquid, a pair of rigidly connected adsorbers charged with a vapor adsorbing material in communication with said evaporator, means to support said adsorbers for swinging movement in steps effected by changes in the weight thereof, such means being constructed to provide a dwell at each end and the middle of the swinging movement, and means controlled by said swinging movement to cut off communication between said evaporator and alternate adsorbers at each end of said movement and activate said adsorbers when said communication is cut off.

12. Refrigerating apparatus of the character described including in combination, an evaporator containing an evaporable liquid, a pair of rigidly connected adsorbers charged with a vapor adsorbing material in communication with said evaporator, means to support said adsorbers for swinging movement in steps effected by changes in the weight thereof, such means being constructed to provide a dwell at each end and the middle of the swinging movement, means to cut off communication between said evaporator and alternate adsorbers at each end of said movement, and means controlled by said movement to activate the adsorbers when said communication is cut off.

13. An adsorber for refrigerating apparatus including a header, a series of pipe lengths secured to said header, each pipe being in communication at one end with said header and closed at the other end, and means to support adsorbent material in each pipe in the form of a hollow cylinder, the length of said cylinder being substantially coextensive with the length of the pipe and the interior of said cylinder being in communication with said header.

14. An adsorber for refrigerating apparatus including a header, a series of pipe lengths secured to said header, each pipe being in communication at one end with said header and closed at the other end, a cylindrical screen in each pipe and concentric therewith, but of smaller diameter, and a solid adsorbent material in the annular space between the outside of the screen and the pipe.

15. Refrigeration apparatus of the char-

acter described, including in combination, a support, a unit comprising a pair of adsorbers charged with vapor adsorbing material balanced on said support so that alternate adsorptions and activations cause said unit periodically to tilt first one way and then the other, and a single source of heat below said support, said adsorbers being so positioned on said unit that one is directly above said source of heat at each end of a tilting movement of said unit, the axis of tilt being below the tops of the adsorbers.

16. Refrigeration apparatus of the character described, including in combination, a support, a unit comprising a pair of adsorbers charged with vapor adsorbing material balanced on said support so that alternate adsorptions and activations cause said unit periodically to tilt first one way and then the other, a single source of heat below said support, said adsorbers being spaced apart at the top and converging toward the bottoms whereby minimum tilting causes one or the other to register with said source of heat.

17. Refrigeration apparatus of the character described, including in combination, a support, a unit comprising a pair of adsorbers charged with vapor adsorbing material balanced on said support so that alternate adsorptions and activations cause said unit periodically to tilt, means to limit the tilting so that the bottom of the lower adsorber is centrally positioned in respect to the axis of tilt and a single source of heat positioned to be directly beneath the bottom of the lower adsorber.

18. Refrigeration apparatus of the character described, including in combination, a support, a unit comprising a pair of adsorbers charged with vapor adsorbing material balanced on said support so that alternate adsorptions and activations cause said unit periodically to tilt, means to limit the tilting so that the bottom of the lower adsorber is centrally positioned in respect to the axis of tilt, a fuel burner positioned to be directly beneath the bottom of the lower adsorber at maximum tilt and means to supply fuel to said burner only when an adsorber is above it.

In testimony whereof they hereunto affix their signatures.

ERNEST B. MILLER.
WALTER L. EDEL.
